Primary Examiner — Eric L Goodman*Assistant Examiner* — John R Yeh(74) *Attorney, Agent, or Firm* — Wayne & Ken, LLC;
Tony Hom(57) **CLAIM**

The ornamental design for a mop cloth, as shown and described.

DESCRIPTION

FIG. 1 is a front elevation view of a mop cloth showing my new design;

FIG. 2 is a back elevation view thereof;

FIG. 3 is a left side view thereof, which is a mirror image of a right side view;

FIG. 4 is a top plan view thereof, which is a mirror image of a bottom plan view; and,

FIG. 5 is the top plan view in unfolded state.

The broken lines represent suture lines that form no part of the claimed design.
